NONABRASIVE CLAMP FOR FLEXIBLE ELECTRICAL CONDUCTORS

Filed Oct. 1, 1945

FIG. 1.

FIG. 2.

FIG. 3.

Andrew Sandy.
INVENTOR.

BY W.B. Harman
ATTORNEY.

It will thus be seen that a simple and efficient non-abrasive clamp for an electrical conductor has been disclosed which possesses the unique advantages of being simply and economically formed and capable in operation of holding a conductor through simple frictional engagement with the same thereby making it possible to support one end of an electrical conductor at a considerable distance from the other without clamping and distorting the electrical conductor or bending it sharply or in any way contributing to the destruction of the insulation or electrical conductor portion thereof.

Having thus described my invention, what I claim is:

1. A non-abrasive clamp for flexible electrical conductors including at least three tubular body members connected by at least two curved channels, at least one of the curved channels connecting the bottom portions of two of the said tubular body members and at least one of the curved channels connecting two of the body members at their top sections, the said tubular body members and curved channels forming a partially enclosed channel including a pair of oppositely disposed reversed curves.

2. A non-abrasive clamp for a flexible elec-

trical conductor including at least three tubular body members connected by at least two curved channels, at least one of the curved channels connecting the bottom portions of two of the said tubular body members and at least one of the curved channels connecting two of the body members at their top sections, the said tubular body members and curved channels forming a partially enclosed channel including a pair of oppositely disposed reversed curves, and a bracket formed thereon for attaching the said clamp to a supporting structure.

ANDREW SANDY.
